CLAIM

The ornamental design for a chandelier, as shown and described.

DESCRIPTION

FIG. 1 is a perspective view of the chandelier;
FIG. 2 is a front elevational view of the chandelier;
FIG. 3 is a rear elevational view of the chandelier;
FIG. 4 is a left side elevational view of the chandelier;
FIG. 5 is a right side elevational view of the chandelier;
FIG. 6 is a top plan view of the chandelier; and,
FIG. 7 is a bottom plan view of the chandelier.

The broken line portions of the drawings are included to show portions of the article that form no part of the claimed design and represent environmental structure only.
